UNITED STATES PATENT OFFICE.

ABRAHAM ZILBERSHER, OF NEW YORK, N. Y.

PASSENGER AND MOVING PICTURE ADVERTISING BUS.

Application filed June 2, 1926. Serial No. 113,196.

This invention relates to an improved device which may be used to carry passengers or used for advertising purposes and has for an object to provide an improved construction wherein the bus may be used for the purposes mentioned without changing any of the construction.

Another object of the invention is to provide a bus which will have the usual appearance of a double deck bus but with the parts so constructed that they may be adjusted to present advertising space to be seen at a distance from the bus and also to present a moving picture.

15 A further object, more specifically, is to provide in a bus means for entertaining the passengers and those outside of the bus and at the same time advertising certain commodities, the structure including a screen and moving picture projecting apparatus positioned in respect to the bus so as to be out of the way of the passengers while ready at all times to function.

In the accompanying drawings—

25 Figure 1 is a side view of a bus disclosing an embodiment of the invention.

Figure 2 is a sectional view through Figure 1 on line 2—2.

30 Figure 3 is a sectional view through Figure 2 on line 3—3.

Figure 4 is a sectional view through Figure 1 on line 4—4.

35 Figure 5 is similar to the upper part of Figure 1 but showing the parts adjusted and ready for use with the projecting machine.

Figure 6 is a detail fragmentary view taken through Figure 5 on line 6—6.

40 Figure 7 is an enlarged detail fragmentary side view showing a bracket and a bracing hook structure embodying certain features of the invention.

Figure 8 is a sectional view through Figure 7 on line 8—8.

45 Referring to the accompanying drawings by numerals, 1 indicates the body of the automobile which is provided with a lower deck 2 and an upper deck 3, each deck being supplied with suitable seats. The lower deck 2 is provided with an entrance door 4 and adjacent this door there is provided an inlet turnstile 5 and an outlet turnstile 6. Adjacent the turnstile 5 is arranged the driver's seat 7. At the front of the body 1 there 50 is provided the usual engine and control mechanism therefor. It will also be evident

that body 1 is mounted on a suitable supporting chassis carried by suitable traction wheels. Arranged adjacent the seat 7 are stair steps 8 which lead from the lower deck to the upper deck so that passengers may freely pass from one deck to the other. The body 1 is provided with suitable rows of windows 9 and 10 on the lower and upper decks.

When the bus is used for advertising purposes, suitable advertising matter 11 is applied to the windows, said matter being placed thereon by any desired method, as for instance, by being painted thereon or by being printed on pasters and the pasters applied to the window panes. Arranged at a convenient point on the lower deck is a radio apparatus 12 which is connected by suitable wiring to the loud speaking units 13 and 14 whereby the passengers on both decks may enjoy music or other matter reproduced by the apparatus 12.

The top or roof 15 is provided with an opening 16 normally closed by the plate 17 having a depending portion 18 at the periphery fitting over the upstanding flange 19 at the periphery of the opening 16. The opening 16 is normally maintained closed, when the bus is in use as a passenger bus 20 but when used principally for advertising, plate 17 is removed and a moving picture apparatus 20 is operated. The pictures from this apparatus are projected through the opening 16 and strike against the screen 21, which screen is pivotally mounted at 22 on the body 1. The screen 21 may be of any desired construction, as for instance, formed with a frame 23 carrying on each side a piece of cloth 24. Preferably a rod 25 is pivotally connected at each side of the screen 21 and their forward ends are formed into suitable hooks 26 which are adapted to fit over pins 27 carried by the brackets 28 connected to the body 1 near each side thereof. It will be noted that each bracket 28 is a substantially U-shaped structure as shown in Figure 8 and at the upper end carries a clamping bolt 29 having a wing nut 30. When the hook 26 is in position as

55 shown in Figures 5, 7 and 8, nut 30 is operated for causing the bracket 28 to pinch hook 26 and thereby lock the parts in position. When the screen 21 has been set to a vertical position as shown in Figure 5, the motion picture apparatus 20 may be operated and if desired, the bus may be moved

2
along at substantially any desired speed. If passengers are carried at this time they cannot see the moving pictures projected on the screen 21 but persons along the street 5 may readily see the pictures as well as see the advertising matter 11. In order to better see the advertising matter arranged in the windows 9 and 10, suitable hooded lamps 31 and 32 are provided, said lamps illuminating the advertising matter without producing a glare in the eyes of pedestrians near the bus. If desired, a camera 34 may be provided at the front of the bus. This camera is 15 shown as a moving picture camera but may be an ordinary still picture camera if desired. A T-shaped member 35 is connected with the camera 34 and is slidingly mounted in the runways 36 and 37. By the use 20 of the T member 35 and the runways 36 and 37, two cameras may be carried but if desired, the moving picture camera may be carried at one time and a still camera at another. 25 From Figures 2 and 3 it will be noted that a talking machine 38 is provided near the radio apparatus, said talking machine being adapted to have advertising matter on the records so that when the machine is in operation it will talk about certain merchandise. For the purpose of convenience, a suitable tool box 39 is provided below the radio apparatus and the talking machine.

As indicated in Figure 2, a suitable push button 40 is provided near the turnstile 6 35 so that the signal to the driver can only be given when a party is ready to leave the bus. The push button 40 is electrically connected with a suitable bell near the driver's seat so that when the button 40 is pushed the 40 bell will ring. At the right of the incoming turnstile 5 is arranged a change making apparatus 41 and immediately in front of the turnstile 5 is arranged a coin box 42 in which the coins are to be put before the 45 turnstile 5 can be operated. This arrangement in regard to the money relieves the driver of attending to change or the proper collection of money.

What I claim is:

In a bus a body provided with a roof having an opening therein, a moving picture screen hingedly connected to the body at the rear end, a bracing link pivotally connected with the screen, said bracing link 55 having at its free end a hook, a bracket secured to said roof, said bracket being bifurcated, a pin carried by the bracket for receiving said hook, a clamping member for squeezing the parts of the bracket together 60 for clamping said hook and thereby prevent accidental disengagement thereof, and a projecting machine carried by said body adapted to project pictures through said opening onto said screen.

ABRAHAM ZILBERSHER.
